UNITED STATES PATENT OFFICE

MAIVE A. OPPY, OF WELCH, WEST VIRGINIA, ASSIGNOR TO AIR WASHERS, INC., OF WELCH, WEST VIRGINIA, A CORPORATION OF WEST VIRGINIA

SEPARATOR

Application filed June 10, 1930. Serial No. 460,229.

This invention relates to a separator and has relation more particularly to a device of this kind of a pneumatic type which is especially intended for use in connection with coal and the like.

It is an object of the invention to provide a separator which eliminates what is generally known as a "middlings product".

The invention also has for an object to provide an apparatus of this kind which operates with substantially no vibration and which discharges clean coal at one end and clean refuse at the other end.

Another object of the invention is to provide a device of this kind which, in addition to a pneumatic means for lifting coal, a revolving drum is provided to also effect a lifting action upon the coal whereby the action of the pneumatic means is rendered more effective particularly as pertains to the separation of fine slate.

The invention consists in the details of construction and in the combination and arrangement of the several parts of my improved separator whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view partly in side elevation and partly in section illustrating a separator constructed in accordance with an embodiment of my invention;

Figure 2 is a view in front elevation of the apparatus as illustrated in Figure 1;

Figure 3 is a detailed sectional view taken substantially on the line 3-3 of Figure 1.

As disclosed in the accompanying drawings, D denotes a drum of desired dimensions but gradually decreasing in diameter from its receiving end toward its discharge end and the wall of said drum is perforated. The smaller end of the drum D carries a relatively narrow annular member 1, the outer face of

which being closed by a head 2. This head 2 at its axial center is provided with an outstanding spindle 3 rotatably engaged with a bearing 4 carried by a cross member 5 comprised in the supporting structure S. The spindle 3 provides means for supporting the smaller end of the drum D while the larger end of the drum carries an outstanding annular rim 6 which rests from above upon the supporting rollers 7 suitably mounted upon the supporting structure S at opposite sides of the vertical center of the drum.

The closed end 2 of the drum D carries an annular bevel gear 8 meshing with a pinion 9 fixed upon and suitably supported by a shaft 10. This shaft 10 is adapted to be driven as desired but preferably through the medium of a pulley 11 indicated by dotted lines in Figure 1, suitably mounted upon said shaft 10 and in driven connection through the belt 12 with the fan shaft 14.

The peripheral wall of the drum D is provided with a series of inwardly disposed and spirally arranged rifle flanges 15, preferably three in number, and the channels resulting between these rifle flanges discharge through the openings 16 provided in the annular member 1 and equidistantly spaced circumferentially thereof. The discharge from these openings 16 is controlled by a sleeve 17 snugly mounted upon the member 1 and provided with openings 18 adapted to be brought into desired register with the openings 16. This sleeve 17 is effectively maintained in desired selective adjustment by a binding screw 19 threaded therethrough for firm contact with the member 1.

Extending a desired distance inwardly of the drum D through the larger or receiving end thereof is a feed chute 20 leading from a suitable source of supply. Underlying the member 1 of the drum D is the upper end portion of a downwardly inclined refuse chute 21. Arranged below the larger or receiving end of the drum D is a chute 22 for carrying off the clean coal.

The supporting structure S below the drum D supports a fan casing 23 in which each of the side walls 24 of the supporting structure forms a part. The discharge of the opening

of the casing 23 faces upwardly and is continued by the oppositely and upwardly inclined imperforate plates 25 terminating closely adjacent the drum D at opposite ends thereof.

The fan shaft 14 carries conventional fan blades 26 and said shaft 14 is adapted to be rotated in any desired manner as from an electrical motor E as indicated by broken lines 10 in Figure 1.

A wall 24 is provided with an air induction opening 27 for the fan casing 23 and said opening is under control of the dampers or shutters 28 herein disclosed as of a sliding 15 type.

In practice, the drum rotates in a direction opposite to the hand of the riffle flanges 15 so that slate or refuse trapped between the riffles will be screwed toward the upper or smaller 20 end of the drum D and discharged out through the openings or discharge ports 16. The blast of air created by the blades 26 beneath the drum passes upwardly into the drum from below through the perforations 25 thereof, said air being of such velocity and pressure in a constant stream to cause the coal to float. The coal will flow downgrade and the expanding or increasing diameter of the drum assures a thinning of the coal bed 30 to afford a more thorough cleaning. The riffle flanges 15 are of such depth to assure therebetween a deep enough bed at the discharge ends thereof to prevent losing an undue amount of air through the openings or ports 16 which would otherwise readily blow through a thin bed. The depth of the riffle flanges 15 is also such to properly trap and convey the separated refuse as it drops and keeps sliding down to the low point of the 40 drum in each channel formed between the riffle flanges. The separated slate or refuse is carried or slid toward the high and small end of the drum by the riffle flanges. As the diameter of the drum reduces, and more especially in the high end portion, less space is left for the slate or refuse and hence it will crowd out any coal, even large pieces of coal, that may be mixed with it. The holes or ports 16 will allow some coal to pass out there- 50 through if they always remain the same size. However, this can be taken care of by proper adjustment of the sleeve 17. The speed of rotation of the drum D will depend upon the amount of slate or refuse delivered within 55 the drum with the coal. This condition can also be readily compensated for by increasing or decreasing the field.

As the openings or ports 16 are closed the accumulation of slate or other refuse within 60 the drum will be correspondingly increased in the small or upper portion of the drum and hence a more sealed bed is formed which will not allow an undue amount of air to blow out through the openings or ports 16. A 65 mass of refuse with a small amount of air

working therethrough makes all coal, either large or small, to come to the top and roll downgrade to pass off with the clean coal over the chute 22.

The dampers or shutters 28 are used to regulate the gross supply of air in sufficient amount to cause the coal to float.

From the foregoing description it is thought to be obvious that a separator constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

A separator comprising a rotatable drum, the wall of which being perforated, spiral riffle flanges carried by the peripheral wall of the drum and extending inwardly thereof, the wall of the drum having discharge openings in communication with the spaces between the riffle flanges at the discharge ends thereof, means for rotating the drum, said drum being tapered from one end toward the other, the discharge openings being in the smaller end portion of the drum, and means for directing a blast of air from below into the drum from substantially one end of the drum to the other.

In testimony whereof I hereunto affix my signature.
